(57) **CLAIM**

The ornamental design for a card box, as shown and described.

DESCRIPTION

FIG. 1 is a left, front, top perspective view of a card box in an open position, showing my new design;

FIG. 2 is a back, bottom perspective view thereof;

FIG. 3 is a left side perspective view thereof in a partially open position;

FIG. 4 is a left side perspective view thereof in a partially closed position;

FIG. 5 is a left, front, top perspective view thereof in a closed position;

FIG. 6 is a front elevation view thereof in an open position;

FIG. 7 is a rear elevation view thereof;

FIG. 8 is a left side elevation view thereof;

FIG. 9 is a right side elevation view thereof;

FIG. 10 is a top plan view thereof; and,

FIG. 11 is a bottom plan view thereof.

The broken lines shown in the drawings illustrate parts of the card box forming no part of the claimed design.

1 Claim, 11 Drawing Sheets
